VALVE CONTROL MEANS

Otto Thiel, Detroit, Mich.

Application February 26, 1943, Serial No. 477,194

7 Claims. (Cl. 137—69)

This application relates to control means for gas-charged-liquid devices, such as carbonators, and particularly to means for controlling the vent valves of such devices.

Control means now known include hollow sealed devices, generally spherical in shape. Because of pressure differentials between the inside and outside of such devices it is necessary to make them of heavy sheet metal and to form their joints very carefully; otherwise collapse is certain. Even where such precautions are taken, very often these devices collapse in use with consequent annoyance and danger.

In some instances, the control means include moving parts outside of the dispensing tank, connected to the tank by flexible tubes, and this is not satisfactory since the exposed parts, outside of the tank, may become blocked or injured, with consequent impairment of their functions.

In the control means here shown, I do not use hollow sealed devices but instead use light gauge, thin sheet metal open end cups. In addition, all of the controlling parts, including these cups, are disposed within the dispensing tank where they are in protected position.

An embodiment according to the foregoing is described in this specification, which refers to the attached drawing, whose single figure diagrammatically shows that embodiment.

The drawing shows a sealed bottom tank 10 whose upper end is closed by a head 11 having a valved vent opening 12 adapted to be closed by a needle valve 13 pivotally connected at its lower end to a lever 14, at a point 15 intermediate the two ends of this lever. The right end 16 of this lever is connected by a vertical link 17 to an open top thin sheet metal cup 18 and the left end 16a of this lever is connected to a counterweight 19, comprising a weight link having weighting nuts threaded onto its lower end. Lever 14 is pivoted to the tank at 20, a fixed pivot. Near the upper end of the weight link is a latching lug 21 which may seat in a latching recess 22 in one arm of a V shaped bracket 23, pivoted on the casing by a fixed pivot 24 and, having the ends of its two arms fastened to an open bottom or inverted thin sheet metal cup 25.

For gas-charged-water, there are the usual inlet and outlet pipes 26 and 27. The vent opening 12 communicates to atmosphere through an exhaust tube 28.

The operation is as follows:

Assume the cycle starts with the parts in the position shown in the drawing. At this time, the water level is low, well below the upper end of 55

the lower cup 18 which is filled with water whose weight has overcome the counterweight and has lowered vent valve 13 to open. The weight of the upper cup 25 has closed latch 21—22 and not until this cup rises, can any of the parts move.

If water is admitted to a level well above cup 18, that cup will lose its weight, being completely submerged, and will no longer oppose the counterweight. When the water level becomes high enough, the upper cup 25 will be lifted and will rock counterclockwise on its pivot 24 to unlatch the counterweight at 21—22, which, being unopposed and unlatched, drops and lifts the valve 13 to close.

If enough water be drawn off, so that the water level drops to free the upper cup, the latter will drop and position its recess 22 to receive lug 21 and lock the counterweight, if and when the latter moves up, out of its lower position, wherein its lug 21 is out of registry with latch recess 22 of the bracket.

As the water level further drops, exposing lower cup 18, the latter, being full, and exposed, will once more have weight and will move up the counterweight to relatch it at 21—22 to the upper cup bracket 23, and to open the valve 13.

This is the desired cycle of operations in this type of device.

The control means shown accomplishes this result without the use of hollow sealed devices or flexible hose connections, etc., and with all the parts within the tank.

Now having described the control means hereof, reference should be had to the claims which follow.

I claim:

1. Control means for the upper head vent valve of a tank having a gas-charged-liquid inlet and a gas-charged-liquid outlet and having a vent, and a valve below it for rising and closing it, or for dropping and opening it, comprising a counterweight for biasing said valve upwardly to close, an open top cup at the lower end of the tank operatively connected to the counterweight and to the valve in such a manner that when it rises it frees the counterweight to drop, and thus lift the valve to close, and when it drops, it overcomes and lifts the counterweight, and lowers the valve to open, means providing a latch for the counterweight to prevent it from rising or falling, and an open bottom cup at the upper end of the tank, operatively connected to the latch in such a manner that when it rises it unlatches or releases the counterweight, freeing it so as to be under the control of the lower cup, and when it drops it

resets the latch in position to seize the counterweight and hold it, if and when the counterweight rises to the latch in response to a lowering of the lower cup.

2. Control means for the upper head vent valve of a tank having a gas-charged-liquid inlet and a gas-charged-liquid outlet and having a vent, and a valve below it for rising and closing it, or for dropping and opening it, comprising a counterweight for biasing said valve upwardly to close, an open top cup at the lower end of the tank operatively connected to the counterweight and to the valve in such a manner that when it rises it frees the counterweight to drop, and thus lift the valve to close, and when it drops, it overcomes and lifts the counterweight, and lowers the valve to open, means providing a latch for the counterweight to prevent it from rising or falling, and an open bottom cup at the upper end of the tank, operatively connected to the latch in such a manner that when it rises it unlatches or releases the counterweight, freeing it so as to be under the control of the lower cup, and when it drops it resets the latch in position to seize the counterweight and hold it, if and when the counterweight rises to the latch in response to a lowering of the lower cup, the cups, the latch, and the counterweight, all being within the tank.

3. Control means for the upper head vent valve of a tank having a gas-charged-liquid inlet and a gas-charged-liquid outlet and having a vent, and a valve below it for rising and closing it, or for dropping and opening it, comprising a counterweight for biasing said valve upwardly to close, an open top cup at the lower end of the tank operatively connected to the counterweight and to the valve in such a manner that when it rises it frees the counterweight to drop, and thus lift the valve to close, and when it drops, it overcomes and lifts the counterweight, and lowers the valve to open, means providing a latch for the counterweight to prevent it from rising or falling, and an open bottom cup at the upper end of the tank, operatively connected to the latch in such a manner that when it rises it unlatches or releases the counterweight, freeing it so as to be under the control of the lower cup, and when it drops it resets the latch in position to seize the counterweight and hold it, if and when the counterweight rises to the latch in response to a lowering of the lower cup, the cups, the latch, and the counterweight, all being within the tank, and interconnected by links or the like also within the tank.

4. Control means for the upper head vent valve of a tank having a gas-charged-liquid inlet and a gas-charged-liquid outlet and having a vent, and a valve below it for rising and closing it, or for dropping and opening it, comprising a counterweight for biasing said valve upwardly to close, an open top cup at the lower end of the tank operatively connected to the counterweight and to the valve in such a manner that when it rises it frees the counterweight to drop, and thus lift the valve to close, and when it drops, it overcomes and lifts the counterweight, and lowers the valve to open, means providing a latch for the counterweight to prevent it from rising or falling, and an open bottom cup at the upper end of the tank, operatively connected to the latch in such a manner that when it rises it unlatches or releases the counterweight, freeing it so as to be under the control of the lower cup, and when it drops it resets the latch in position to seize the counterweight and hold it, if and when the coun-

terweight rises to the latch in response to a lowering of the lower cup, the control means including a lever within the tank, pivoted between its ends on a fixed pivot, and having at its ends pivotal connections to links, one of which connects one end of the lever to the lower cup, and the other of which, in effect, forms part of the counterweight, and connects the lever to the rest of the counterweight, with the lower end of the valve being connected to the lever at a point between the lever pivot and the end thereof connected to the lower cup.

5. Control means for the upper head vent valve of a tank having a gas-charged-liquid inlet and a gas-charged-liquid outlet and having a vent, and a valve below it for rising and closing it, or for dropping and opening it, comprising a counterweight for biasing said valve upwardly to close, an open top cup at the lower end of the tank operatively connected to the counterweight and to the valve in such a manner that when it rises it frees the counterweight to drop, and thus lift the valve to close, and when it drops, it overcomes and lifts the counterweight, and lowers the valve to open, means providing a latch for the counterweight to prevent it from rising or falling, and an open bottom cup at the upper end of the tank, operatively connected to the latch in such a manner that when it rises it unlatches or releases the counterweight, freeing it so as to be under the control of the lower cup, and when it drops it resets the latch in position to seize the counterweight and hold it, if and when the counterweight rises to the latch in response to a lowering of the lower cup, the upper cup having an extending arm pivotally mounting it, with the latch comprising interengaging formations on the counterweight and on said arm, released by upward pivotal movement of the upper cup.

6. Control means for the upper head vent valve of a tank having a gas-charged-liquid inlet and a gas-charged-liquid outlet and having a vent, and a valve below it for rising and closing it, or for dropping and opening it, comprising a counterweight for biasing said valve upwardly to close, an open top cup at the lower end of the tank operatively connected to the counterweight and to the valve in such a manner that when it rises it frees the counterweight to drop, and thus lift the valve to close, and when it drops, it overcomes and lifts the counterweight, and lowers the valve to open, means providing a latch for the counterweight to prevent it from rising or falling, and an open bottom cup at the upper end of the tank, operatively connected to the latch in such a manner that when it rises it unlatches or releases the counterweight, freeing it so as to be under the control of the lower cup, and when it drops it resets the latch in position to seize the counterweight and hold it, if and when the counterweight rises to the latch in response to a lowering of the lower cup, the control means including a lever within the tank, pivoted between its ends on a fixed pivot, and having at its ends pivotal connections to links, one of which connects one end of the lever to the lower cup, and the other of which, in effect, forms part of the counterweight, and connects the lever to the rest of the counterweight, with the lower end of the valve being connected to the lever at a point between the lever pivot and the end thereof connected to the lower cup, the upper cup having an extending arm pivotally mounting it, with the latch comprising interengaging formations on the

counterweight and on said arm, released by upward pivotal movement of the upper cup.

7. Control means for the upper head vent valve of a tank having a gas-charged-liquid inlet and a gas-charged-liquid outlet and having a vent, and a valve below it for rising and closing it, or for dropping and opening it, comprising a counterweight for biasing said valve upwardly to close, an open top cup at the lower end of the tank operatively connected to the counterweight and to the valve in such a manner that when it rises it frees the counterweight to drop, and thus lift the valve to close, and when it drops, it overcomes and lifts the counterweight, and lowers the valve to open, means providing a latch for the counterweight to prevent it from rising or falling, and an open bottom cup at the upper end of the tank, operatively connected to the latch in such a manner that when it rises it unlatches or releases the counterweight, freeing it so as to be 20 under the control of the lower cup, and when it

5 drops it resets the latch in position to seize the counterweight and hold it, if and when the counterweight rises to the latch in response to a lowering of the lower cup, the control means including a lever within the tank, pivoted between its ends on a fixed pivot, and having at its ends pivotal connections to links, one of which connects one end of the lever to the lower cup, and the other of which, in effect, forms part of the counterweight, and connects the lever to the rest of the counterweight, with the lower end of the valve being connected to the lever at a point between the lever pivot and the end thereof connected to the lower cup, the upper cup having an extending arm pivotally mounting it, with the latch comprising interengaging formations on the counterweight and on said arm, released by upward pivotal movement of the upper cup, with one of the latch formations being on the upper end of the counterweight link.

OTTO THIEL.
